UNITED STATES PATENT OFFICE

2,545,944

RESERVOIR EXHAUST FOR CORE BLOWING MACHINES

Robert W. Ellms, Lakewood, Ohio, assignor to The Osborn Manufacturing Company, Cleveland, Ohio, a corporation of Ohio

Application June 26, 1948; Serial No. 35,413

9 Claims. (Cl. 22—10)

1

This invention relates as indicated to novel reservoir exhaust means for core blowing machines and the like and more particularly to a device which avoids the disadvantages of prior art arrangements.

Mold and core blowing machines have long been employed by the foundry industry, and certain features of their construction have become quite standardized. In those machines which are of the semiautomatic type pneumatic means are quite generally employed to operate the box clamping means and other moving parts. Such machines usually comprise an air chamber, a sand hopper, and a sand chamber or reservoir laterally moveable into and out of respective subjacent engagement therewith. Means are provided for supporting a core box below the sand reservoir when the latter is in blowing position, such means being adapted to be elevated to bring the top of such core box into engagement with the lower end of the reservoir.

In operation, the sand reservoir is filled from the sand hopper and shifted laterally beneath the blow head of the machine. The core box is then elevated slightly to tightly engage the lower end of the sand reservoir and high pressure air is admitted to the blow head of the machine to blow the sand from the reservoir into the core box. When the blow has been completed, the valve admitting air pressure to the blow head is closed and an exhaust valve is opened to relieve the blow head and reservoir of air pressure prior to removal of the core box and reciprocation of the reservoir for another charge of sand. The venting of the air in the blow head and sand reservoir has in practice posed several difficult problems. As in the case of most automatic and semiautomatic equipment, time is a very important factor and it is therefore desired to exhaust the air pressure as quickly as possible to permit further operation of the machine. In practice, however, such air pressure has been vented through a small exhaust valve in the head of the machine located as far as possible from the sand reservoir. If this valve is too large, the sudden outflow of air creates excessive turbulence and a good deal of sand is carried along. Such sand not only causes very rapid wearing of the valve but is also discharged into the room where the machine is located making for very unsatisfactory working conditions. By employing a sufficiently small vent opening, such turbulence within the sand reservoir may be lessened but the operation of the machine is slowed in consequence, since the next step in operation must await complete vent-

2

ing of the air pressure. While this may be only a matter of some seconds, it is nevertheless of consequence in the case of a high production machine of the type here in question.

5 It is therefore a primary object of my invention to provide a reservoir exhaust for core blowing machines which will be very rapid in its action.

Another object of my invention is to provide an 10 exhaust which will not be subject to excessive wear and will require but little maintenance.

Still another object is to provide such exhaust which will not discharge sand into the outer atmosphere.

15 Other objects and advantages will appear as the description proceeds.

To the accomplishment of the foregoing and related ends, said invention then comprises the features hereinafter fully described and particularly pointed out in the claims, the following description and the annexed drawing setting forth in detail certain illustrative embodiments of the invention, these being indicative, however, of but a few of the various ways in which the principle 25 of the invention may be employed.

In said annexed drawing:

Fig. 1 is a side elevational view partly in cross-section of a standard well-known type of a core blowing machine having the exhaust of my invention incorporated therein;

30 Fig. 2 is a plan view of my novel exhaust valve;

Fig. 3 is a sectional view taken along the line 3—3 on Fig. 2;

35 Fig. 4 is a view taken along the line 4—4 on Fig. 3; and

Fig. 5 is a view taken along the line 5—5 on Fig. 3.

Referring now more particularly to said drawing, the general construction of the typical core blowing machine illustrated in Fig. 1 will first be described. Such machine comprises a base 1 supporting four columns 2 carrying a sand hopper 3 and a blow head 4 by their upper ends. Blow head 4 includes an air pressure chamber 5 and a blow chamber 6 adapted to be placed into communication or sealed from one another by actuation of diaphragm valve 7.

Mounted below blow chamber 6 and hopper 3 for lateral reciprocation into and out of respective subjacent engagement therewith is a sand reservoir 8 having an upper adaptor 9. Such sand reservoir is adapted to be thus reciprocated by air pressure introduced into cylinder 10 acting

upon piston 11 against the force of a coil spring 12.

A table or platen 13 is carried by the upper end of a jackscrew 14 mounted in base 1. Such table is adapted to be elevated or lowered through operation of such screw by means of handwheel 15. Adjustably mounted on table 13 are two horizontal clamps 16 and 17 adapted to be respectively positioned by means of adjusting screws 18 and 19. Clamp 17 is backed by the piston 20 attached to diaphragm 21. By admitting air pressure to the left-hand side of such diaphragm as viewed in Fig. 1, clamp 17 may be caused to securely hold core box 22 in cooperation with clamp 16. When such air pressure is released, spring 23 will cause clamp 17 to move to the left to release such core box. Sand reservoir blow plate 24 is provided with apertures 25 coinciding with similar apertures in the top of the core box whereby sand may be blown from such reservoir into such core box. Screened vents such as 26 will likewise preferably be provided in the core box to ensure proper compacting of the sand therein. The core box may be either horizontally or vertically split to provide for subsequent removal of the core. Reciprocation of the sand reservoir as above described is controlled by means of the hand operated valve 28 and the treadle operated valve 27 is for controlling the blowing and venting of the reservoir after the blow.

It is common practice to provide a circular sand reservoir cover bolted to the side of such reservoir to permit inspection of the interior of the reservoir and manual cleaning thereof should such become necessary. I have provided a novel reservoir exhaust located in the position commonly occupied by such cover plate and in a preferred embodiment comprising a diaphragm valve of large diameter. As shown in Figs. 2-5 inclusive, such valve may comprise a cast iron seat member 29 and a cast iron cover 30 bolted thereto by means of bolts 31. Valve seat member 29 is secured over annular opening 32 in the side of reservoir 8 by means of studs 33 and nuts 34. Wire mesh screen 35 is clamped between member 29 and the reservoir extending across opening 32 and sealed about its periphery by means of a glue gasket 36. Such screen may, for example, be No. 30 mesh Phosphor bronze, although the exact mesh size preferably employed may vary somewhat depending upon the type of sand being used in the core blowing operation.

As best shown in Figs. 3 and 4, member 29 is formed on its inner side with a plurality of radially disposed ribs 37 adapted to engage the outer side of wire mesh screen 35. Small protuberances or buttons 38 between such ribs likewise contact the screen. A large portion of the screen area is therefore available for escape of air therethrough which then passes out through central valve opening 39. Surrounding such central opening 39 is an annular groove 40 connecting with two laterally extending escape passages 41 and 42. A rubber diaphragm 43 is interposed between cover 30 and valve seat member 29 and a connection 44 is provided for the attachment of an air pressure line whereby to operate the valve. A wear-disk or washer 45 is bolted to the center of diaphragm 43 to engage the inside of cover 30 and prevent undue wear of the diaphragm during exhaust.

Referring now more particularly to Figs. 1 and 5, a flexible air line 46 is provided interconnecting a small aperture 47 in the blow head and a

passage 48 in boss 49 of valve seat member 29. This passage 48 leads into the side of opening 39, thereby providing free escape of air from the upper part of the machine when the valve is open.

The operation and advantages of my new exhaust will now be understood and appreciated. During the blow operation the valve is closed by means of air pressure admitted to cover 30 through opening 44. The pressure on the reservoir side of the diaphragm will be less than on the cover side due to flow of air from the reservoir under the diaphragm out to the exhaust ports. Once the valve is seated, the area of the diaphragm subject to air pressure on the cover side is obviously much greater than area of orifice 39 so the valve remains firmly closed. The moment the blow pressure is shut off and the pressure within cover 30 simultaneously relieved, diaphragm 43 is unseated and the air trapped in the reservoir escapes through screen 35, opening 39 and lateral escape passages 41 and 42. The air escapes very rapidly from the reservoir as a result of the large area of screen 35, but the sand is of course prevented from being carried along thereby. Any sand which accumulates against the screen serves as an additional filter and, since the grains of sands suitable in molding and core blowing operations are always irregular in shape, the body of sand which may accumulate against the screen will be porous in nature. Such sand serves as a desirable additional filtering medium. If after long use the screen should become clogged, it is a simple matter to change the same. Since the valve assembly is readily removable, no separate clean-out port need be provided. In fact, if desired, the entire valve may be mounted in a hinged door closing such port to facilitate both such cleaning of the reservoir and replacement of the screen. Extended tests, however, have indicated that this will probably not be often necessary. The use of the valve above described permits an extremely rapid drop of pressure within the reservoir from high pressure to low pressure, but I have found that if no additional means is provided there is a disproportionate time lag in the venting of the remaining low pressure air. For this reason I provide the additional vent 47 in the upper part of the machine connecting with passage 48 to the outer side of screen 35. While such vent 47 is too small to provide for sufficiently rapid escape of high pressure air (a larger opening would cause turbulence and transportation of the sand) nevertheless by providing such direct communication with the exterior atmosphere the escape of the low pressure air remaining within the reservoir after venting of the high pressure air through screen 35 is obtained. The exact location of opening 47 is not of great consequence as long as it is above the level of the sand remaining in the reservoir and preferably sufficiently thereabove to avoid any likelihood of sand being picked up and transported by the escaping air. Furthermore, since there is no spring or similar means to seat the diaphragm after the high pressure has been relieved in the reservoir, such diaphragm valve remains open allowing continued escape of the low pressure air.

It will thus be seen that by placing my exhaust directly on the reservoir I have taken advantage of a factor which was previously a definite detriment, namely I obtain a venting of the high pressure air directly from the reservoir and thereby avoid any tendency to lift sand into the head of the machine where its presence is most objection-

able. Prior art designers have been faced with the dilemma that any venting means in the head of the machine providing for a quick escape of the high pressure air would necessarily cause turbulence and transportation of the sand into the head of the machine and its escape into the outer atmosphere. I have found that my exhaust operates efficiently whether the sand level in the reservoir is slightly below, partially covers, or completely covers the screen 35. The term "sand" as employed herein is of course intended to include other like materials employed in the formation of cores and molds in the foundry.

The exceedingly rapid drop of the reservoir pressure permits rapid unclamping and lowering of the core box so that the under surface of the blow plate 24 does not drag across the core box surface when the reservoir is returned to the fill position. This action avoids undue wear and consequential leakage at the joint between blow plate and core box.

Other modes of applying the principle of the invention may be employed, change being made as regards the details described, provided the features stated in any of the following claims or the equivalent of such be employed.

I therefore particularly point out and distinctly claim as my invention:

1. In a mold and core blowing machine or the like, a sand reservoir having a large opening in the side thereof, blow means above said reservoir operative to blow sand from said reservoir into a core box or the like, filter means adapted to allow passage of air through said opening but adapted to prevent passage of sand therethrough, an air escape passage leading from said opening, and valve means adapted to control flow of air through said opening operative to place said opening in communication with the outer atmosphere only when a blowing operation is not taking place.

2. In a core blowing machine or the like, a sand reservoir, blow means above said reservoir operative to blow sand from said reservoir into a core box or the like, said reservoir having air exhaust means comprising a large opening in the side thereof positioned to extend at least partially below the level of said sand when said reservoir is filled, filter means disposed across said opening effective to prevent the escape of sand therethrough, and a valve on said reservoir externally of said opening adapted to control escape of air therethrough, said valve being adapted to close for the duration of the operation of said blow means to prevent passage of air through said opening at such time and to open after completion of the blow to place said opening in communication with the outer atmosphere so that air remaining in said reservoir under pressure may escape.

3. In a mold and core blowing machine, a blow head, a sand reservoir adapted to receive air under pressure from said blow head, two escape passages to relieve air pressure from within said blow head and reservoir, one said passage leading from a large opening in said reservoir provided with sand filter means and the other said passage leading from said blow head and adapted to transmit a much smaller air flow than said first passage, and valve means controlling escape of air through said passages.

4. In a core blowing machine or the like, a blow head, a sand reservoir, a valve adapted quickly to exhaust high pressure air directly from a side of said reservoir, filter means disposed

and arranged to prevent passage of sand from said reservoir through said valve, a small air vent in said blow head spaced from said reservoir, and a passageway leading from said vent and communicating with the reservoir side of said valve between said valve and filter means.

5. In a core blowing machine, a blow head, a sand reservoir, a valve mounted on said reservoir adapted to exhaust air pressure directly from within said reservoir, filter means disposed and arranged to prevent passage of sand from said reservoir through said valve, a small air vent in said blow head spaced from said reservoir, and a passageway leading from said vent and communicating with the reservoir side of said valve between said valve and filter means.

6. In a core blowing machine or the like, a sand reservoir, a blow head, said reservoir being adapted to be positioned beneath said blow head and having a large opening in the side thereof, a screen disposed across such opening to prevent the passage of sand therethrough, a diaphragm valve exteriorly of said screen operative to place such opening in communication with the outside atmosphere after completion of a blowing operation, a small air vent in said blow head well above the sand level of said reservoir, and a passageway connecting said vent with said valve at a point between said screen and said diaphragm valve.

7. In a core blowing machine or the like, a sand reservoir, a sand hopper, a blow head, said sand reservoir being alternately reciprocable beneath said sand hopper and blow head and having a large opening in the side thereof, a fine wire mesh screen across such opening, a valve seat member exteriorly of said screen and having a central orifice of less diameter than such opening, projections on said member contacting and supporting said screen, a diaphragm exteriorly of said member operative to seal such orifice in said member, a cover for said diaphragm, means adapted to admit high pressure air to said cover during the core blowing operation to force said diaphragm to seal such orifice, an air exhaust passage in said valve seat member opening toward the inner side of said diaphragm and therefore communicating with such orifice when the latter is not sealed by said diaphragm, a small air vent in said blow head well above the sand level of said reservoir, and a passageway connecting said vent with such central orifice of said valve seat member.

8. In a core blowing machine or the like, a sand reservoir, said reservoir having a large opening in the side thereof, a screen disposed across said opening to prevent the escape of sand therethrough, a valve seat member exteriorly of said screen and having a central orifice of less diameter than said opening, projections on the inner side of said member contacting and supporting said screen during passage of exhaust air therethrough, an annular groove in the outer side of said member surrounding said central orifice, a diaphragm disposed exteriorly of said member operative to seal said orifice, an outer cover for said diaphragm, means adapted to admit high pressure air to said cover during the core blowing operation to force said diaphragm to seal said orifice, and an air exhaust passage leading from said annular groove.

9. In a core blowing machine or the like, a sand reservoir, said reservoir having a large opening in the side thereof, a fine wire mesh screen across said opening adapted to prevent escape of sand therethrough, a valve seat member ex-

teriorly of said screen and opening and having a central orifice of less diameter than said opening, radially disposed ribs on the inner side of said member, buttons on said member between said ribs, said ribs and buttons contacting and supporting said screen during passage of air therethrough, an annular groove in the outer side of said member surrounding such central orifice, a diaphragm disposed exteriorly of said member operative to seal such orifice from said groove, an outer cover for said diaphragm, means adapted to admit high pressure air to said cover during the core blowing operation to force said diaphragm to seal said orifice, and a laterally extending air exhaust passage in said valve seat 15 member leading from said annular groove.
